CLAIM

The ornamental design for a serving tray defined by a tempered glass panel bounded by a one-piece rim of injection molded polymeric/copolymeric synthetic materials, as shown and described.

DESCRIPTION

FIG. 1 is a top perspective view of a serving tray defined by a tempered glass panel bounded by a one-piece rim of injection molded polymeric/copolymeric synthetic material showing my new design;

FIG. 2 is a bottom perspective view thereof;

FIG. 3 is a side elevational view with the opposite side being identical thereto;

FIG. 4 is an end elevational view with the opposite end view being identical thereto;

FIG. 5 is an enlarged fragmentary cross-sectional view taken generally along line 5—5 of FIG. 1 showing the cross-sectional configuration of the rim and its integral handle relative to a peripheral edge of the tempered glass panel; and,

FIG. 6 is a cross-sectional view taken generally along line 6—6 of FIG. 1.
